UNITED STATES PATENT OFFICE

126,084

DESIGN FOR A BOWLING ALLEY PIN SPOT

Carl H. Weicker, Toronto, Ontario, Canada, assignor to The Brunswick-Balke-Collender Company, Chicago, Ill., a corporation of Delaware

Application August 14, 1940, Serial No. 94,411
In Canada May 30, 1940

Term of patent 3½ years

To all whom it may concern:

Be it known that I, Carl H. Weicker, a citizen of the United States, residing in the city of Toronto, county of York, Province of Ontario, Dominion of Canada, have invented a new, original, and ornamental Design for a Bowling Alley Pin Spot, of which the following is a specification, reference being had to the accompanying drawing, forming a part thereof.

I claim:

The ornamental design for a bowling alley pin spot, as shown.

CARL H. WEICKER.
